UNITED STATES PATENT OFFICE.

EDWARD POSSON, OF CHICAGO, ILLINOIS.

REFRIGERATOR-CAR.

No. 892,447.

Specification of Letters Patent.

Patented July 7, 1908.

Application filed December 13, 1907. Serial No. 406,297.

To all whom it may concern:

Be it known that I, EDWARD POSSON, a citizen of the United States, residing at Chicago, in the county of Cook and State of Illinois, have invented certain new and useful Improvements in Refrigerator-Cars, of which the following is a specification.

The object of my invention is to provide a car with ice chambers in the ends thereof formed by movable bulkheads which can be displaced when desired so as to make the entire length of the car available for carrying freight.

Referring to the drawings—Figure 1 is a longitudinal section of a freight car embodying my invention. Fig. 2 is a cross section looking toward the end of the car from the inside thereof; and Fig. 3 is a sectional plan view.

20 The floor 15, the end sill 16, the end wall 17 and the roof 18 are similar to the corresponding parts in cars well-known in the art and are here mentioned merely in order that the relation of the parts essential to my invention may be clearly illustrated.

25 The floor 15 ends at a little distance from the end wall 17, the edge being bounded by the Z-bar 19. The sheet metal lining 20 has one edge secured under said Z-bar and extends thence across the bottom of the ice chamber and up a certain distance on the end wall 17. The end and side walls have a sheet metal lining 20^a. On the lining 20 at the bottom of the chamber there are placed 30 frames or grids 21 formed of spaced members having portions cut away on their under edges, as indicated by the reference numeral 22, so as to permit water to flow freely in any direction across the bottom lining 20. Drain 35 outlets 20^b are provided in the floor so as to permit the discharge of the water formed by the melting ice. The grids 21 do not fill the entire bottom of the ice chamber, but narrow spaces are left on either side of the car in 40 which are placed the tracks 23 formed of sheet metal.

45 The movable bulkhead is formed of vertical channel beams 24 each filled with a wooden beam 25. These wooden beams 50 are thicker than the flanges of the channels and spaced horizontal boards or slats 26 are nailed to the projecting wooden members. The spaces between the vertical frame members 24—25 are filled with inclined vanes 30^a 55 of a design well-known in the art, which are intended to deflect the air downwardly as it

enters the ice chamber from the central part of the car. Extending across the bottom of the bulkhead is an angle iron 27 attached to the vertical frame members 24—25 and 60 adapted to have one flange rest on the Z-bar 19. Above this angle iron 27 is a long door 28 hinged horizontally on its upper edge at 29 and having hooks 30 which overlap the angle iron 27. When desired to obtain access to the lower part of the ice chamber from the interior of the car this door can be raised for the purpose.

Opposite the slats 26 there is a metal open-work lining 31, which is adapted to retain the 70 ice in the ice chamber. At the lower corners of the bulkhead there are rollers 32 adapted to roll on the tracks 23. On each side of the ice chamber at the top there is a rack 33. A shaft 34 extends across the top of the bulk- 75 head having journal bearings in the tops of the posts 24—25. On each end of this shaft there is a small gear wheel 35 adapted to engage the rack 33. An angle iron 36 extending across the top of the car forms an abut- 80 ment adapted to hold the bulkhead at its top. The said bulkhead has a cross beam 37 across the top, and gusset-plates 39 are riveted to this and to the vertical posts 24—25. On the shaft 34 there is fixed a collar 38 hav- 85 ing holes in which a wrench or crowbar may be inserted for the purpose of rotating said shaft. Across the inner face of the bulkhead near its bottom is an angle iron 40 which forms a ledge to support the grids or frames 90 42. These are hinged to the end wall of the car, the angle iron 41 being adapted to support the hinged ends. The slats of each grid 42 are held together by long bolts 43^a and 44^a 95 passing through the spacers 43 and 44. When the ice is out of the ice chamber each grid 42 may be lifted up and folded back against the end wall of the car. The said end wall is lined with vertical slats 45 and these are notched as indicated by the reference numerals 46 and 47, so as to accommodate the spacers 43 and 44. A slide 48 with 100 an appropriate guide is provided, as shown in Figs. 1 and 2. This slide is adapted to be raised into the space 49 when the grid 42 is 105 folded back and then it will drop over one of the spacers 44 and hold the grid in place. Clips 50 extend a short distance from the inner face of the end wall of the car and have holes in their ends adapted to register with 110 the holes 51 in the vertical posts 24—25 so that when the bulkhead is pushed close

against the end wall of the car, pins can be pushed through the registering holes so as to assist in holding the bulkhead in place. Such pins can readily be inserted by raising

- 5 the door 28. Across the top of the ice chamber extend braces 52 permanently pivoted at 53 to the end wall of the car and engaging the top of the bulkhead by means of removable pins 54. When it is desired to move the 10 bulkhead back against the end wall of the car, the pins 54 may be withdrawn and the braces 52 be dropped so as to hang against the end wall of the car. Lugs 55 are provided on the end wall which will register with 15 the pin sockets on the bulkhead and by means of these registering members the same pins 54 may be employed to lock the bulkhead close against the end wall 17.

Removable covers 56 are provided in the 20 car roof immediately above the ice chambers, through which ice may be introduced and which may be opened when desired for ventilating purposes. The ice in the ice chamber is represented by the reference numeral 57.

- 25 As shown in the drawings, the apparatus is arranged so as to carry ice in the ice chamber, but when this is not desired and it is wished to utilize the space of the ice chamber for carrying ordinary freight, then the grids 30 42 may be folded back against the end wall 17 and retained in this position by means of the slides 48, the braces 52 may be detached, by withdrawing the pins 54 and then said braces may be swung down against the end 35 wall of the car. By rotating the shaft 34, the whole bulkhead will be carried back against the end wall of the car. There is a space left above the cross slats 26 through which an operator can reach to remove the 40 pins 54 and in order to apply a wrench to the collar 38. When the bulkhead has been traversed back against the end wall of the car it may be locked in this position by means of the pins 54 engaging the clips 55 and by 45 means of other pins which may be passed through the holes 51 and the corresponding holes in the clips 50. The reverse operation of opening out the bulkhead from the end wall is sufficiently obvious from the foregoing.

50 It will be observed that I have provided a refrigerator car in which the ice space may be readily utilized for carrying freight when it is not desired to use it for ice. The change 55 may be made easily and quickly and the mechanism by which it is effected is of a simple character that is not likely to get out of order.

I claim:

- 60 1. A refrigerator car having a movable partition across the end thereof whereby the space at the end of the car may be separated off as an ice chamber or may be connected to the central part of the car.

65 2. A refrigerator car having a transverse

movable partition, horizontal tracks on which the partition is supported, and means for shifting the partition along said tracks to or from the end wall of the car.

3. A refrigerator car having a partition, 70 rollers thereon, suitable tracks on which the rollers are adapted to travel, and means for shifting the partition to or from a wall of the car.

4. A refrigerator car having a movable 75 partition adapted in one position to separate off a portion of the interior of the car to serve as an ice chamber, and in another position to go close against the boundary wall of the car so as to permit the whole interior 80 of the car to be utilized as one continuous space.

5. A refrigerator car having a movable transverse partition, rollers thereon, suitable tracks for the rollers extending at right 85 angles to the end wall of the car, and means for shifting the partition to or from the end wall of the car.

6. A refrigerator car having a movable transverse partition, a horizontal rotatable 90 shaft journaled in the upper edge of said partition, gear pinions on said shaft, and horizontal racks extending lengthwise of the car and adapted to be engaged by the said pinions. 95

7. A refrigerator car having a movable transverse partition, a horizontal rotatable shaft journaled in the upper edge of said partition, gear pinions at the ends of said shaft at the upper corners of the partition, and horizontal racks supported on the side walls 100 of the car and adapted to be engaged by said pinions.

8. A refrigerator car having a transverse movable partition with supporting rollers at 105 the bottom thereof, and means at the top for shifting the partition to or from the end wall of the car.

9. A refrigerator car having a transverse movable partition, and mechanism for shifting the partition to or from the end wall of the car, said mechanism being such as to constrain the partition to move always parallel to the end wall of the car. 110

10. A refrigerator car having a transverse 115 movable partition, and a false bottom hinged to the end wall of the car and adapted to be folded up and back against the same or be turned forward and down so as to reach across from the end wall to the said partition. 120

11. A refrigerator car having a transverse movable partition, an end wall lining consisting of spaced vertical slats, and a false bottom hinged to the end wall and consisting of slats staggered with respect to the end wall slats, so that the false bottom may be folded up against the end wall and its slats will go between those of the end wall. 125

12. A refrigerator car comprising a trans-

130

verse movable partition, means for locking it at a certain definite position from the end wall, and means for locking it close against the end wall.

5 13. A refrigerator car comprising a transverse movable partition, and braces pivoted to the end wall of the car at one end of each and having their other ends adapted to de-

tachably engage the partition, said braces being adapted to hang down close to the end wall of the car when their ends are disconnected from the partition.
